ADAM FISHER, OF PALISADES PARK, NEW JERSEY, ASSIGNOR TO INTERNATIONAL PATENTS DEVELOPMENT COMPANY, OF WILMINGTON, DELAWARE, A CORPORATION OF DELAWARE

TENSION CONTROL FOR LABEL PASTING BELTS

Application filed September 28, 1931. Serial No. 565,397.

This invention relates to an apparatus for applying liquid adhesive to surfaces preliminary to a gluing operation, for example, for applying glue to the marginal portion of labels adapted to be applied to containers. The present invention may be employed in various operations wherein it is desired to evenly and uniformly distribute adhesive over given surfaces, but to facilitate an understanding thereof it will here be described in connection with the art of affixing labels to cylindrical cans.

The general process of labelling cans, of which the present invention is only a part, may be briefly described as follows:

The unlabeled can is fed into a machine which rolls it to a stack of labels which are maintained at an approximately constant level by control means located at the bottom of the stack. Immediately before the can reaches the stack of labels a thin strip of paste or glue is applied longitudinally along the side wall of the can. This strip of glue is called "pick-up glue". As the can rolls onto the stack of labels its progress is so timed that the pick-up glue comes into contact with one end of the topmost label of the stack causing the label to adhere to the can and thereby wrap itself around the can as the latter continues to roll across the stack. The glue which secures the opposite end of the label after the label is completely wrapped around the can is applied by an endless belt which passes through a glue-pot and slides over the stack of labels at said opposite end. When the label is partially wrapped around the can, the can with the label thus attached is diverted from the stack of labels. This movement pulls the opposite end of the

label out from under the endless belt or paste-applying belt, as it is called. Means are thereafter provided for fitting and sealing this free end of the label to the can. As will readily be seen, when the topmost label is thus pulled away from the stack the paste-applying belt immediately contacts the next label and prepares it for the following can.

The present invention is directed to the means for guiding and tensioning the endless belt and relates specifically to improved

means for securing the proper engagement between the belt and the stack of labels.

In devices heretofore employed for this purpose much difficulty has been encountered in so guiding the belt across the label as to provide an even spread of glue at all points. The principal trouble arises from the glue scraping off of the belt on the edge of the stack of labels, which action results not only in a loss of glue but also in a general smearing of the labels which is reflected in the untidy appearance of the labeled cans. This fault is caused by improper tension of the belt and the consequent inability to properly guide the same.

Another problem has been encountered in adjusting the label pasting device to accommodate labels of varied sizes.

The principal object of this invention is to provide improved means for tensioning and guiding a label pasting belt whereby the paste is evenly and uniformly applied to the labels without danger of loss or damage occasioned by scraping of the belt against the edges of the labels.

A further object is to provide improved means for easily and efficiently adjusting the tension of the label pasting belt.

A further object is to provide improved means for tensioning and guiding a label pasting belt by means which can be quickly and efficiently adjusted to varied sizes of labels.

Fig. 1 is a side elevation of the label pasting apparatus with parts shown in vertical section.

Fig. 2 is an enlarged perspective view of the carriage and guide lever with the belt omitted.

Fig. 3 is a plan view of the belt supporting arm with the guiding and tensioning means assembled thereon with the belt omitted.

Referring to the drawing, the reference Figure 1 designates a glue pot of known construction in which is mounted means, also known, for applying a thin strip of glue or other adhesive to the outside surface of an endless belt, or paste-applying belt 2 which courses therethrough. This paste-applying

belt 2 is supported outside the glue-pot 1 by guide pulleys 3 and 4 pivotally mounted on one end of a supporting arm 5 which is secured at its other end to a bracket 6 attached in suitable manner to the glue-pot 1. Supporting arm 5 is adjustably secured to said bracket 6 by means of a clamp screw 7 which extends through a slot 8 longitudinally positioned at one end of said supporting arm 5. As best shown in Fig. 3 the pulleys 3 and 4 are formed with depressed or grooved central portions to reduce friction and to keep the glue from smearing. A label bed 9 is positioned with one end directly under the paste-applying belt 2 at a point approximately midway between the glue-pot 1 and the guide pulleys 3 and 4. Said label bed 9 forms supporting means for a stack of labels 10 which extends slightly over the top thereof and is kept at approximately this level by means (not shown) at the bottom of the label bed 9. The label bed 9 extends at right angles to the paste-applying belt 2 in the direction away from the supporting arm 5 so that the extreme end of the portion of the top surface of the stack of labels 10 is directly under the paste-applying belt 2.

As thus far described the apparatus is of known construction.

30 Slidably arranged on the supporting arm 5 is a block or carriage 11 adapted to be locked thereto by a bolt 12. Intermediately pivoted on said carriage 11 on the side toward the paste-applying belt 2 is a guide lever 13 comprising two guide arms 14 and 15, a belt channel or slideway 16 formed between said guide arms, a finger 17 projecting from one of said guide arms, and a pressure control arm 18. Finger 17 which projects from 40 one of said guide arms, for example arm 14, is adapted to fit between the upper and lower runs of paste-applying belt 2 and for that purpose is grooved or slotted to minimize friction. The opposite arm is truncated to 45 facilitate threading the paste-applying belt 2 into place. The belt channel or slideway 16 is of slightly greater width than that of paste-applying belt 2 and is provided with longitudinal shoulders 19 adapted to receive 50 the marginal portions of the paste-applying belt 2. Shoulders 19 provide a depressed or grooved central portion 20, to minimize friction and to prevent the glue from smearing, and, preferably, extend the full length 55 of the channel 16, at the ends of which they are bluntly tapered.

To facilitate the proper positioning of label bed 9 and the stack of labels 10 the guide lever 13 is formed with transverse shoulders 60 21 and 22. Shoulder 22 is adapted to accommodate the side of the label bed 9. Shoulder 21 is preferably positioned at a point opposite the forward end of channel 16.

The guide arms 14 and 15 and the finger 17 65 of guide lever 13 are yieldingly pressed into

engagement with the labels 10 by means of a spring 23 interposed between the pressure control arm 18 and the supporting arm 5. Pressure control arm 18 is provided with a plurality of holes 24, each adapted to receive 70 one end of spring 23 according to the amount of pressure desired. The anchoring means for the other end of spring 23 comprises a base plate 25 provided with a longitudinal slot 26 in the central portion thereof, an upstanding flange 27, a pin or stud bolt 28 projecting from said flange, and a hole 29 in said pin 28 adapted to engage the other end of the spring 23. A bolt and clamp washer 30 extends through the slot 26 and into the 80 supporting arm 5.

The operation of the device is as follows:

The block or carriage 11 is moved so that the shoulder 21 of the guide arm 13 is in close contact with the edge of the labels and shoulder 22 is in contact with the edge of the label bed 9. When the block has thus been adjusted to accommodate the particular size of label to be pasted, the carriage 11 is locked into position by bolt 12, and the apparatus is ready for operation. The motive power for driving the belt may be applied at any convenient point but is usually applied at the glue-pot 1.

The paste-applying belt 2 rotates or 95 courses in a clockwise direction (Fig. 1) through the glue-pot 1 and emerges with a thin strip of glue deposited on the top central portion thereof. This thin strip of glue is prevented from smearing by virtue of the depressed central portions of the guide pulley 3 and the channel or slideway 16. As the portion of the belt 2 with the glue thus applied reaches the stack of labels 10, it is 100 pressed against the top label by finger 17, which is actuated by spring 23, and the glue is thereby smeared over the surface of the label. It should be particularly noted that in view of the juxtaposition of the forward end of the slideway 16 (nearest the glue-pot 1) and the transverse shoulder 21, the paste-applying belt 2, as it leaves the channel 16, 105 cannot possibly scrape against the edge of the stack of labels 10 by virtue of the fact that the edge of the labels 10 are supported 110 against said shoulder 21 which is at a point directly below the said end of the slideway 16. It should also be noted in this connection that the spot where the paste-applying belt 2 comes into contact with the labels 10 is determined by both the location of the transverse shoulder 21 and the height of the longitudinal shoulders 19 in slideway 16. In the preferred embodiment of this invention the longitudinal shoulders 19 are sufficiently 115 above the transverse shoulder 21 to permit the paste-applying belt 2 to come into contact with the label at a point sufficiently removed from the edge of the label stack 10 to avoid any possibility of the paste-apply- 120 125 130

ing belt 2 scraping against the said edge. In actual practice it has sometimes been found desirable to construct the longitudinal shoulders 19 of such height that the paste-applying belt 2 contacts the label stack 10 at a point substantially removed from the edge thereof. When the longitudinal shoulders 19 are thus constructed a skilled operator can vary the point of contact to points nearer the edge if desired by moving the labels slightly away from the transverse shoulder 21.

As will be seen, the successful operation of the apparatus depends not only on the features above noted but also upon the proper tension of the paste-applying belt 2 to insure uniformity of contact with the labels and on the proper pressure of the guide arms 14 and 15 and the finger 17 against the labels. As has already been mentioned the preliminary tension of the paste-applying belt 2 is effected by adjusting the length of the supporting arm 5 by means of the slot 8 and the clamp screw 7. The tension of the belt 2 and the pressure of the guide arms 14 and 25 15 and the finger 17 against the labels is further adjusted by adjusting the tension of the spring 23. This is effected either by loosening the bolt and clamp washer 30 and adjusting the position of the base plate 25 on which the spring 23 is anchored to supporting arm 5 or by securing the spring 23 to another of the holes 24 in pressure control arm 18.

In conclusion it is again noted that although the above apparatus has been described in an embodiment adapted for use in connection with the art of affixing labels to cans it is not intended to restrict the present invention thereto. The invention may be used in other fields wherein it is desired to distribute adhesive or other substances over given surfaces. Also the invention may be constructed in varied forms and the specific structure hereinabove described may be modified and changed without altering the essence of the invention as covered in the following claims.

I claim:

1. A guide and tensioning means for the lower paste applying run of a label pasting belt comprising a fixed support, a lever pivoted on said support, said lever comprising an arm adapted to rest on the labels and having means for guiding the belt into engagement with the labels, and spring means interposed between the lever and the support for holding the arm yieldingly in engagement with the labels.

2. A guide and tensioning means for the lower paste applying run of a label pasting belt comprising a fixed support, a lever intermediately pivoted on said support, one arm of said lever adapted to rest on the labels and provided with means for guiding the belt into engagement with the labels, and spring means interposed between the

other arm of the lever and the fixed support for yieldingly pressing the opposite arm into engagement with the labels.

3. A guide and tensioning means for the lower paste applying run of a label pasting belt comprising a fixed support, a lever intermediately pivoted on said support, one arm of said lever adapted to rest on the labels and provided with means for guiding the belt into engagement with the labels, a spring engaged at one end with the other arm of the lever for pressing the guide arm into engagement with the labels and an anchoring member for the other end of the spring mounted on the fixed support.

4. A guide and tensioning means for the lower paste applying run of a label pasting belt comprising a fixed support, a lever intermediately pivoted on said support, one arm of said lever adapted to rest on the labels and provided with means for guiding the belt into engagement with the labels, a spring engaged at one end with the other arm of the lever for pressing the guide arm into engagement with the labels, an anchoring member for the other end of the spring mounted on the fixed support, and means for adjusting said anchoring member to vary the effective force of the spring exerted on said lever.

5. A guide and tensioning means for the lower paste applying run of a label pasting belt comprising a fixed support, a lever intermediately pivoted on said support, one arm of said lever adapted to rest on the labels and provided with means for guiding the belt into engagement with the labels, a spring engaged at one end with the other arm of the lever for pressing the guide arm into engagement with the labels, an anchoring member for the other end of the spring adjustably mounted on the fixed support and adapted to be locked into fixed engagement therewith.

6. A guide and tensioning means for the lower paste applying run of a label pasting belt comprising a fixed support, a lever intermediately pivoted on said support, one arm of said lever adapted to rest on the labels and provided with means for guiding the belt into engagement with the labels, and spring means adjustably interposed between the other arm of the lever and the fixed support for yieldingly pressing the opposite arm into engagement with the labels.

7. A guide and tensioning means for the lower paste applying run of a label pasting belt comprising a fixed support, a lever intermediately pivoted on said support, one arm of said lever adapted to rest on the labels and provided with means for guiding the belt into engagement with the labels, and a spring engaged at one end with the fixed support and adjustably engaged at the other end with the lever.

8. A guide and tensioning means for the

- lower paste applying run of a label pasting belt comprising a fixed support, a carriage slidably arranged thereon and adapted to be locked thereto, a lever pivoted on said carriage, said lever comprising an arm adapted to rest on the labels and having means for guiding the belt into engagement with the labels, and spring means interposed between the lever and the support for holding the arm yieldingly in engagement with the labels.
9. A guide and tensioning means for the lower paste applying run of a label pasting belt comprising a fixed support, a carriage slidably arranged thereon and adapted to be locked thereto, a lever intermediately pivoted on said carriage, one arm of said lever adapted to rest on the labels and provided with means for guiding the belt into engagement with the labels, a spring engaged at one end with the other arm of the lever for pressing the guide arm into engagement with the labels, an anchoring member for the other end of the spring mounted on the fixed support, and means for adjusting said anchoring member to vary the effective force of the spring exerted on said lever.
10. A guide and tensioning means for the lower paste applying run of a label pasting belt comprising a fixed support, a carriage slidably arranged thereon and adapted to be locked thereto, a bellcrank lever pivoted on said carriage, one arm of said lever adapted to rest on the labels and provided with means for guiding the belt into engagement with the labels, a tension spring adjustably engaged at one end with the other arm of the lever for pressing the guide arm into engagement with the labels, an anchoring member for the other end of the spring mounted on the fixed support, said anchoring means comprising a base plate having a slot therein, an upwardly extending arm, a pin projecting from said arm and adapted to receive one end of the spring and means for bringing the base plate into locked engagement with the fixed support at intermediate points within the slot.
11. In a pasting apparatus for labels comprising an endless belt, means for supporting the belt comprising an arm extending transversely above the labels, belt supporting pulleys positioned at either side of the labels and means for applying paste to the belt, means for guiding and tensioning the lower paste applying run of the belt comprising a carriage slidably arranged on the belt supporting arm and adapted to be locked thereto, a pin projecting from said carriage, a lever intermediately pivoted on said pin comprising guiding arms extending on one side of the pivotal axis thereof, a pressure control arm provided with a plurality of holes on the other side of the said pivotal axis, and a belt channel between the guide arms and having a pair of edge supporting shoulders

for the edge portion of the belt, a transverse finger projecting from one of said guide arms between the upper and lower runs of the belt and adapted to rest on the labels, a spring secured at one end to the pressure control arm through any one of the plurality of holes provided thereon and secured at the other end to an anchoring member adjustably mounted on the belt supporting arm.
